DUMP CAR

John P. Anderson, Crafton, Pa., assignor to
Pressed Steel Car Company, Inc., Pittsburgh,
Pa., a corporation of Pennsylvania

Application May 17, 1938, Serial No. 208,444

7 Claims. (Cl. 105—272)

The invention pertains generally to dump vehicles having doors forming the side walls of the body and opening outwardly and downwardly as the body is tilted for dumping. The invention 5 pertains specifically to a mechanism for controlling the opening and closing of the doors through movement of the body relative to the underframe.

Railway dump vehicles having tilting bodies 10 provided with doors forming end or side walls of the body are generally automatic in operation. Usually a body tilting mechanism actuated by fluid pressure is mounted upon the vehicle underframe and in engagement with the vehicle body. 15 A separate mechanism for controlling the movements of the side and end doors is connected to the doors and mounted on the body or the underframe. The body in normal position acts through the door controlling mechanism to maintain the doors locked in closed position and the body in 20 moving from normal to tilted or dumped position and back to normal position actuates the said mechanism to control the opening movements of the descending door by the rate of tilting of the body and positively move the open door to closed 25 position as the body moves to normal position. Usually the door mechanism includes a means for automatically retaining the door on the rising side of the body closed whilst the body is out 30 of normal position. The lading within the car body is exposed to the weather and oftentimes becomes wet and freezes to the side walls, or the lading may be of a damp sticky nature and naturally adheres to the walls of the body. It sometimes happens that the door on the descending side of the body strikes an obstruction at the 35 sides of the tracks and cannot open when the body is tilted. For these reasons it is preferable to provide the door controlling mechanism with means which release the descending door for opening solely under forces of gravity and weight of lading and which positively close the door as the body is righted. Such a door mechanism leaves the door free to open or remain closed 40 at the tilting side of the body while permitting the body to move from normal to dumped position and back again without injury to the door controlling or body tilting mechanisms.

An object of the invention is to provide a dump 50 vehicle with an automatic door controlling mechanism of the character described which will hold the doors closed when the body is in normal position, which will release the descending door for opening as the body is tilted for dumping, and which will positively close the opened door 55 when the body is returned to normal position.

Another object of the invention is to provide 60 a door mechanism of the character described with means whereby the opening movement of the descending door of the tilting body is con-

trolled by movement of the body and the door is actuated solely by gravity and the weight of lading against the door.

A further object of the invention is to provide 5 such a door mechanism with means for maintaining the door on the rising side of the body closed as the body moves from normal to dump position and back to normal position.

In the drawings forming part of this specification, Fig. 1 shows a vertical transverse section 10 through a railway dump car embodying the invention and having the body in normal position; Fig. 2 shows a similar section through the car with the body in fully tilted position; Fig. 3 shows a section on lines 3—3 of Fig. 1; Fig. 4 is a section on lines 4—4 of Fig. 1; Fig. 5 is a view on line 5—5 of Fig. 1 at the side of the car showing the connections between the locking bars, the body and the underframe; Fig. 6 is a section 15 taken on lines 6—6 of Fig. 1 showing the end 20 bracing of the body and the disposition of the door mechanism beneath the lading retaining sloping end wall of the body; Fig. 7 shows a detail of the opening in the end bracing for passage 25 of door mechanism.

Referring now in detail to the drawings, reference character 1 indicates the car underframe comprising a center sill structure 2 having laterally disposed members 3 secured to each side thereof and spaced longitudinally thereof. Said 30 members 3 have bearing surfaces adjacent the outer ends thereof for supporting the body in normal position and in dumping position. The outermost surfaces 4 are preferably concave to provide a pivotal support for the dumping body. 35

The body is indicated generally by the reference character 5 and comprises longitudinally disposed sills 6 and side sills 7 with transverse diaphragms 8 connecting the sills 6 and transverse diaphragms 9 connecting the adjacent sills 40 6 and side sills 7. The side walls of the body are formed of doors 10 pivotally mounted on hinge pins 11 journaled in bearings secured to the side sills 7. A lading retaining floor 12 extends over the longitudinal sills 6 and 7 and extends beyond the inner lower face of the side doors 10. The end lading retaining walls 13 of the body are preferably inclined inwardly of the body and connected to the floor 12. These walls 13 are braced longitudinally of the body by means of end posts 14 connected to the longitudinal sills 6 and angle posts secured to the other sills of the body. The outer flanges of posts 14 are joined by plate 15 forming a cover for the door controlling mechanism to be hereinafter described. This plate 15 has an outwardly extending offset 16 which overlaps a toe plate 17 secured to the underframe 2 to prevent injury to an operator standing on the end platform of the car. 55

Each door controlling mechanism comprises a 60

crank 18 pivotally mounted on a shaft 19 journaled in bearings preferably secured to the end posts 14. Each end post has an opening 32 in the web thereof to permit the passage of the 5 crank 18. The outer end of the crank 18 has a pin 20 journaled therein for the purpose of connecting the crank to the link 21 pivotally mounted on a pin 22 journaled in a downward extension 23 of the door stake 24. It will be noted that 10 the link 21 is in two parts, the outer part being threaded into the inner part for the purpose of longitudinal adjustment of link 21. The inner end of the crank 18 is bifurcated adjacent the shaft 19 and a crank 25 is mounted on the shaft 15 19 within the said bifurcation. Said crank 25 extends above the bifurcation of crank 18 and has its outer end pivotally connected by means of pin 26 to a link 27. The inner end of the link 20 27 is operably connected to the underframe and the preferred form of connection comprises a link 28 disposed transversely of the underframe. One end of link 28 is pivotally connected to the 25 opposite side of the underframe by means of the pin 29 and the other end of link 28 is pivotally connected by means of the pin 30 to a bracket 31 mounted on the body adjacent the shaft 19. It will be observed upon reference to Fig. 1 of the drawings that each door forming the respective side walls of the car has two such door controlling mechanisms connected thereto, said mechanisms being disposed beyond the end wall 13 of the body and housed between the end wall 13 and the end plate 15.

Upon reference to Fig. 3 of the drawings, it 35 will be observed that cranks 18 on opposite sides of the same end of the body are in substantially the same transverse vertical plane and that the inner end of the crank 18 at one side of the car is offset inwardly and the inner end of the opposite 40 crank is offset outwardly of the said plane. This offsetting is for the purpose of connecting the links 27 and 28 so as to prevent interference, when the body is dumping, between the links 28 having their ends alternately connected to the 45 body and to the underframe.

Referring now to Fig. 1 of the drawings showing the body in normal position, the forces of the lading within the body and gravity acting on each door 10 tends to rotate the associated 50 crank 18 inwardly of the car which rotation is resisted by the link 27 and its associated link 28 acting through the crank 25 in engagement with the bifurcation in crank 18. Therefore, link 27 is in compression whilst the body is in normal 55 position.

When the body is tilted about the right side of the underframe and the body bearing moves on to the underframe bearing surface 4, cranks 18 and 25, mounted on shaft 19 secured to the 60 body, move away from the underframe, placing link 27 in tension and causing crank 25 to rotate inwardly of the car and away from crank 18. Crank 18 being then free to move can rotate inwardly of the car as the door 10 opens under 65 the forces of gravity and the lading within the body. From the above it is obvious that the rate of opening of the door 10 is dependent upon the rate at which the tilting body moves crank 25 away from crank 18 and that the sole means 70 actuating the door is the force of gravity and weight of lading upon the door. If for any reason the door should be stopped intermediate its closed and fully opened positions, the body can continue its dumping movement without injury 75 to the door mechanism. The door mechanism

as disclosed in the drawings is so proportioned that the door reaches a fully opened position before the body reaches its maximum dumping angle. For the purpose of stopping the door after it reaches its fully opened position, which is a 5 position at or below the plane of the floor of the body, the stop 32 engages the door stake extension 23 and prevents further rotation of the door on its hinge pin 11.

When the body is righted so as to be returned 10 from the position shown in Fig. 2, to that shown in Fig. 1, the link 27 is placed in compression, rotating cranks 25 and 18 in a direction toward the adjacent side of the car, thereby causing door 15 10 to rotate to closed position as the body reaches 15 normal position.

On the left or rising side of the body, during the above described movements of the body, link 28 through its attachment to the car body, by means of bracket 31 and pin 30, moves with the 20 body and maintains the mechanism associated with the rising side of the body in the same position relative to the door and body as when the body is in normal position, thereby retaining the door in closed position. 25

When the car body is tilted about the left side of the underframe, the same movements of the door mechanism attached to the door on the left side take place as previously described for the mechanism attached to the door on the right side 30 of the body.

It will be observed upon reference to Fig. 2 of the drawings that the body in tilting has a small lateral movement relative to the underframe and that the links 28 are not pivoted to the underframe in the longitudinal tilting axis of the body. For the purpose of providing for this lateral movement of the body and to compensate for the difference in tilting axis of the links 28 and body, the links 28 have a slotted connection to the underframe. Obviously these slotted connections will be unnecessary if the body moves about fixed trunnions or the links are pivoted to the underframe on the tilting axis of the body.

This application is a substitute for abandoned application, Serial No. 115,966, filed December 15, 1936, and is a continuation in part of my co-pending application, Serial No. 390,731, filed September 6, 1929. 45

To those skilled in the art of designing and building door controlling mechanisms for tilting body dump vehicles many changes in the detail construction of the various members and within the scope of the appended claims will suggest themselves. It is to be understood I do not wish to limit myself to details of construction as illustrated by the drawings except as made necessary by the scope of the appended claims. 50

Having thus described the invention what I 55 claim as new and desire to secure by Letters Patent is:

1. In a dump vehicle in combination, an underframe, a body supported thereon in stable equilibrium and tilting to opposite sides thereof, doors forming opposite side walls of the body and hinged adjacent the floor thereof, an arm depending from each door at each end thereof, a crank and link connection between each door arm and the adjacent end of the body and of such design as to rotate inwardly and upwardly with the opening of the door, a link pivoted to the body adjacent the end of each door and extending transversely of the underframe to a pivotal connection therewith so as to move with the body when the latter tilts about the side of 70 75

the underframe to which the transverse link is connected, a crank and link connection between each said transverse link and the body adjacent said connection of the transverse link and body, and means on adjacent cranks engaging to restrain rotation of the first-named crank when the body is in normal position and when the adjacent side of the body is elevated above the underframe, said crank and link connection to the transverse link being controlled thereby so as to rotate relatively to the body and underframe when the body moves relative to said transverse link.

2. In a dump vehicle, an underframe, a body supported on the underframe in stable equilibrium when in normal position and pivoting toward either side of the underframe when out of normal position, doors forming side walls of the body and hinged adjacent the floor thereof, a crank on the body adjacent each end of each door, a link connection between each said crank and door, said crank and link forming a compression lock for the respective door when the body is in normal position, and means associated with each crank, the adjacent side of the body and the opposite side of the underframe for maintaining said compression lock when the body is in normal position and when the side of the body adjacent the door is out of engagement with the underframe, each said means including a member pivotally mounted on the body and normally in engagement with said crank and an operable connection between said means and underframe whereby movement of the body in dumping about the adjacent side of the underframe actuates said means to release the said crank for rotation to permit opening of the door and positively actuates the crank to close the door when the body is returned to normal position.

3. In a dump vehicle, an underframe, a body supported on bearings spaced laterally of the underframe and selectively tilttable on said bearings to either side of the underframe, doors forming the side walls of the body and hinged adjacent the floor thereof, independent mechanisms at each side of the body and spaced longitudinally of the doors for controlling the respective doors, each said mechanism including a shaft mounted on the body adjacent the respective door, a crank pivoting on said shaft, a link connecting said crank and door below said hinge connection thereof, a second crank pivoting on said shaft, a link disposed transversely of the underframe and having one end connected to the body adjacent the respective door and the other end connected to the opposite side of the underframe, a link connection between said second crank and the said transversely disposed link and an abutment on one of said cranks engaging the other crank for limiting relative pivotal movement in one direction between said cranks.

4. In a dump vehicle, in combination, an underframe, a lading body tilttable thereon and provided with doors hinged adjacent the floor of the body to form side walls thereof, each door being provided with a portion adjacent each end thereof depending below the hinge connection and moving beneath the plane of the floor of the body when the door swings on the hinge connection, a crank mounted on the body adjacent each end of each door, a link connection between each

crank and the adjacent depending portion of the door, an abutment member rotatably mounted on the body adjacent each crank and movable relative thereto and means associated with the opposite side of the underframe, the adjacent side of the body and the abutment member for rotating the abutment member alternately away from and toward the adjacent door when the body is tilted and then righted about the adjacent side of the underframe and for maintaining the abutment member fixed relative to the associated crank to prevent rotation thereof when the body is dumping to the opposite side of the underframe.

5. In a dump vehicle of the character described, in combination, an underframe, a body supported thereon and tilttable toward either side thereof, said body including end walls rigid with the body and reinforced by upright posts secured to the body adjacent each side of the end wall, side walls for said body comprising doors hinged adjacent the floor of the body and extending between said rigid end walls, and door controlling mechanisms mounted on the end posts adjacent each door, each mechanism having a suitable portion extending through an aperture in the supporting post and connected with the door.

6. In a dump vehicle in combination, an underframe, a body supported thereon for selective tilting movement about each side of said underframe, doors forming opposite side walls of said body and hinged adjacent the floor thereof, a door controlling mechanism mounted on the body adjacent each door for locking the doors in closed position when the body is horizontal, for selectively releasing the door at the discharging side of the body for opening and for returning the opened door to closed position as the body moves in dumping, each mechanism including a crank pivoted to the body, a link connection between each crank and adjacent door, an abutment pivoted to the body adjacent each crank and normally engaging therewith and an operable connection between each abutment, the adjacent side of the body and the opposite side of the underframe for selectively moving the abutment from and to normal position in controlling the door at the discharging side of the body as the body moves in dumping.

7. In a dump vehicle in combination, an underframe, a body comprising longitudinally disposed side sills extending substantially the length of the body, intermediate longitudinal sills, transverse sills connecting said longitudinal sills, end posts extending above each said intermediate sill at each end thereof and secured thereto, each said end post having a substantially vertical outer face portion and an inner face extending outwardly and upwardly from the associated sill, a floor plate supported by said longitudinal sills, end walls supported by said inner faces of the end posts and connected with said posts and floor plate, doors forming body side walls and hinged to said side sills, controlling mechanisms for each door disposed between the inner and outer faces of said end posts, each mechanism including a member pivotally supported upon the adjacent end post and extending through an aperture in the post, and means supporting said body upon said underframe for tilting towards the opposite sides thereof.

JOHN P. ANDERSON.
